CENTRIFUGAL SEPARATING BOWL

Olof Einar Fröding, Stockholm, Sweden, assignor
to The De Laval Separator Company, New
York, N. Y., a corporation of New Jersey

Application August 8, 1930, Serial No. 473,867,
and in Sweden August 29, 1929

3 Claims. (Cl. 233—46)

When separating, by means of continuously operating centrifuges, liquids which are more or less intimately mixed and which contain solid matters in suspension, a greater or smaller part 5 of the solid matters is deposited in the centrifugal bowl, and when the deposition has grown to a certain point the machine can no longer operate in the way intended, but must be stopped for cleaning. To avoid this objection a number 10 of different constructions and methods have been tried.

In one common type of centrifugal bowl, which is rotated by means of a vertical spindle, the peripheral wall is concentric with the axis and 15 the mixture is fed through a central tube and thence outward to the lower peripheral part of the bowl. The bowl is usually equipped with a superposed pile of spaced-apart conical sheet 20 iron discs, spaced from the bowl wall, to facilitate the separation of the mixed liquids. If, for example, this mixture is an oil contaminated with water and solids, a greater or smaller portion of the impurities are separated. The separated water collects between the bowl wall and 25 the outer edges of the discs until so much has accumulated that it begins to outflow continuously through channels between the top disc and the bowl top. With correct adjustment of the central distance of the outlets for water and 30 oil respectively, static equilibrium is reached so that the pressure of the water is equal to the pressure of the oil, analogous to what takes place between two columns of liquid exposed to the influence of the force of gravity in communicating vessels. This principle was known and 35 applied in the earliest constructions of milk separators.

Part of the solid impurities, especially those 40 which have about the same specific gravity as the water, flow out together with the water through said channels and are thus removed continuously. Some of the impurities have, however, a higher specific gravity than the water and these are separated out and deposited on 45 the bowl wall. The result will then finally be that the annular chamber between the pile of discs and the wall of the bowl entirely fills with solid matters so that the bowl can no longer operate.

50. In bowls of this construction or similar constructions it has been attempted to counteract said deposition of solids by providing for a strong flow of the heavier separated liquid or other heavy liquid continuously or intermittently 55 through the bowl and especially through its

peripheral portion. In this way a certain quantity of the solid matters can be flushed out through the outflow channels, but experience has shown that the method is not effective in most cases because, in spite of the strong flow of 60 liquid upwardly along the wall of the bowl, the heaviest matters cannot be moved upward owing to the centrifugal force, but stick to the bowl wall. The method is also undependable in that the large quantity of flushing liquid easily may 65 cause an emulsion with the lighter liquid, the result of which is an incomplete separation. Moreover, a separation of solid matters occurs in the outflow channels, which, in constructions of 70 this type, are approximately parallel with the generating lines of the conical discs, so that said channels become clogged.

The problem of continuously removing the separated solids has also been attempted to be solved by providing another type of centrifugal bowl, which differs from the bowl first described in that the bowl wall extends at an angle to the axis of rotation with openings or nozzles arranged around the periphery along a line most distant from the axis. The separation of the 80 liquids and the discharge of the lighter liquid take place as in the bowl first described, but the separated heavier liquid, together with the solid matters, travels outward toward said peripheral openings, the dimensions of which are such that, 85 with the pressure of liquid prevailing at them, the quantity of heavier liquid separated per time unit is discharged through them. The separated solid matters slide along the bowl wall to said openings, where they are flushed out with the 90 heavier liquid. In continuous separation a peripheral part of the bowl is thus filled with heavier liquid, whereas the central part is filled with lighter liquid, as is also the case with the construction first described.

The difference in the way the bowls operate is, however, that in the second described construction the equilibrium between said layers of liquid is not static but dynamic. If, for instance, the content of heavier liquid in the mixture of liquids sinks to nil during the separating process, the quantity of heavier liquid contained in the bowl will at first go out through the peripheral openings and then the lighter liquid will discharge the same way. Even before the content of heavier liquid has dropped to this point, there is risk that the same thing will happen, and such a construction of the bowl is thus in many cases not suitable and has not been universally employed.

The present invention comprises a centrifugal

110

bowl of such construction that the separated solid matters are continuously removed by the separated heavier liquid, static equilibrium also prevailing between the separated liquids contained in the bowl.

The drawing is a vertical sectional view of such a centrifugal bowl. The body or hood *a* is held on the bottom *b* by the lock ring *c*. The central feed tube *k* carries the mixture to be separated into the bottom channel or channels *d* whence the mixture flows into the bowl, is distributed through the discs *e*, and is separated as in the bowls hereinbefore described, the lighter liquid discharging through the openings *f*. The heavier liquid is carried into the peripheral part of the bowl and discharges continuously through the channels *h* arranged in the bottom *b*.

Such shape has been given to the body *a* that the solid impurities, which are separated from the lighter liquid and move out towards it under the influence of the centrifugal force, slide down to the openings *g* of the channels *h*. These channels, which are used as outlets for the heavier liquid, extend approximately in radial direction from the centre line of the bowl as well as approximately horizontally, i. e., in nearly the direction of the centrifugal force, so that no separation of solid matters on the walls of the channels takes place owing to the centrifugal force.

By locating the openings *f* and *g* at proper relative distances from the axis of rotation, static equilibrium between the two bulks of separated liquids is secured, and if, therefore, for instance, the content of heavier liquid in the mixture of liquids sinks to nil, the static equilibrium between the two bulks of liquids will be maintained.

The invention is susceptible of embodiment in a greater number of different forms. It is, for instance, possible to mount the bowl in such manner on the spindle that the top of its cone-shaped hood is turned downwards, it is also possible to arrange the bowl for rotation around a horizontal axis.

It is also possible to supply the mixture of liquids to the bowl in such manner that the distribution of the liquid in the pile of discs takes place from that side of the pile of discs which touches the conical hood.

The discharge of the separated liquids from the bowl can also be varied in known ways. In a bowl rotating on a vertical axis, for instance,

both outlets can be placed on the upper side of the bowl, or both on the lower side, or they may be arranged on opposite sides.

When treating certain liquids which can be comparatively easily separated it is not necessary to use a pile of discs, the invention being capable of embodiment in the so-called open bowl.

The invention does not exclude the use, in cases where it is found advantageous, of a strong flow of the heavier separated liquid, or other heavy liquid, for better flushing of the bowl, as hereinbefore described. When used, it is most suitable to introduce the extra flow of liquid through a separate system of channels provided in the bowl in such manner that such flow does not reduce the efficiency of the bowl, as, for example, is disclosed in the British Patent No. 10,314, of 1908.

Having now fully described my invention, what I claim and desire to protect by Letters Patent is:

1. A centrifugal bowl provided with a straight discharge passage extending from the peripheral part of the bowl approximately radially inward toward and at substantial right angles to the bowl's axis of rotation and integral with the bowl so as to have no movement of rotation independently thereof, said passage having free, continuous communication with the interior of the bowl.

2. A centrifugal bowl provided with a straight discharge passage extending from the peripheral part of the bowl toward its axis of rotation in a direction substantially parallel to the lines of centrifugal force and integral with the bowl so as to rotate therewith, said passage having free, continuous communication with the interior of the bowl.

3. A centrifugal bowl for continuous separation of liquids containing solid matters in suspension having a peripheral wall inclined to the axis and along which the separated solids are adapted to slide to a narrow circumferential pocket most distant from the axis of rotation and to which the separated heavier liquid is also carried, the bowl having outlet channels of restricted cross-section, each of the channels extending inwardly from said pocket towards and at substantially a right angle to the axis of rotation of the bowl and opening at both ends at a right angle to said axis of rotation, said channels having free, continuous communication with the pocket.
